CLAIM

The ornamental design for a shoe outsole, as shown and described.

DESCRIPTION

FIG. 1 is a rear perspective view of a shoe outsole showing my new design;

FIG. 2 is a bottom view thereof;

FIG. 3 is a front perspective view thereof;

FIG. 4 is an enlarged view of FIG. 1 with environmental portions removed for clarity;

FIG. 5 is an enlarged view of FIG. 2 with environmental portions removed for clarity; and,

FIG. 6 is an enlarged view of FIG. 3 with environmental portions removed for clarity.

The broken lines immediately adjacent to the shaded area define the bounds of the claimed design and form no part thereof. The broken lines showing the remainder of the shoe represent unclaimed subject matter and form no part of the claimed design. The unshaded region between the shaded areas forms no part of the claimed design.
